UNITED STATES PATENT OFFICE

102,148

DESIGN FOR AN ELECTRIC FOOD MIXER OR SIMILAR ARTICLE

George T. Scharfenberg, Chicago, Ill., assignor to
Chicago Flexible Shaft Company, Chicago, Ill.,
a corporation of Illinois

Application September 24, 1936, Serial No. 64,996

Term of patent 14 years

To all whom it may concern:

Be it known that I, George T. Scharfenberg, a citizen of the United States, residing at Chicago, in the county of Cook and State of Illinois, have invented a new, original, and ornamental Design for an Electric Food Mixer or Similar Article, of which the following is a specification, reference being had to the accompanying drawing, forming part thereof.

In the drawing:

Fig. 1 is a perspective view of an electric food

mixer or similar article showing my new design;

Fig. 2 is a front view thereof;

Fig. 3 is a section on the line 3—3 of Fig. 2 showing a plan view of the base;

Fig. 4 is a side view thereof, and

Fig. 5 is a rear view thereof.

I claim:

The ornamental design for an electric food mixer or similar article substantially as shown.

GEORGE T. SCHARFENBERG.
